(57) **CLAIM**

The ornamental design for an automobile headrest attachment to reduce or eliminate the possibility of whiplash, as shown and described.

DESCRIPTION

FIG. 1 is a top plan view of an automobile headrest attachment to reduce or eliminate the possibility of whiplash showing my new design;

FIG. 2 is a bottom plan view thereof;

FIG. 3 is a right side elevational view thereof;

FIG. 4 is a left side elevational view thereof;

FIG. 5 is a right end elevational view thereof;

FIG. 6 is a left end elevational view thereof;

FIG. 7 is a bottom perspective view thereof;

FIG. 8 is a top perspective view thereof; and,

FIG. 9 is a side view of the automobile headrest attachment to reduce or eliminate the possibility of whiplash in use with the environment and automobile occupant shown in broken lines.
